[57] CLAIM

The ornamental design for a biopsy forceps handle, as shown and described.

DESCRIPTION

FIG. 1 is a left-side elevational view of the biopsy forceps handle;

FIG. 2 is a right-side elevational view thereof;

FIG. 3 is a three-quarter's perspective view of rear, left and topsides of the invention;

FIG. 4 is an enlarged top plan view thereof;

FIG. 5 is an enlarged bottom-view thereof; and,

FIG. 6 is a front elevational enlarged view of the invention.

The broken line showing of the probe and hand in FIGS. 1-5 is for illustrative purposes only and forms no part of the claimed design.

FIG. 1

FIG. 2

FIG. 3

FIG. 4

FIG. 5
